CLAIM

The ornamental design for a cat scratching pad, as shown and described.

DESCRIPTION

FIG. 1 is a front perspective view of a cat scratching pad, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the cat scratching pad in a folded state thereof;

FIG. 10 is a front perspective view showing the cat scratching pad in a fully folded state thereof;

FIG. 11 is an enlarged detail view of area 11 in FIG. 1 thereof; and,

FIG. 12 is an enlarged detail view of area 12 in FIG. 1.

The broken lines in the drawings illustrate the portions of the cat scratching pad, which form no part of the claimed design. The dash-dot-dash broken lines encircling the enlarged views are for annotative purposes only and form no part of the claim thereof.
